UNITED STATES PATENT OFFICE.

WILLIAM H. UPTON AND HENRY C. STOLL, OF NEW YORK, N. Y.

INTERNAL-COMBUSTION ENGINE.

1,221,633.

Specification of Letters Patent.

Patented Apr. 3, 1917.

Application filed April 12, 1915. Serial No. 20,806.

To all whom it may concern:

Be it known that we, WILLIAM H. UPTON, M. D., and HENRY C. STOLL, citizens of the United States of America, and residing at 5 New York, in the county of New York and State of New York, have invented new and useful Improvements in Internal-Combustion Engines, of which the following is a specification.

10 This invention relates particularly to engines of the four cycle type.

The objects of the invention are to improve and simplify the valve mechanism and increase the efficiency generally of such 15 engines.

These objects we have accomplished by employing a rotary valve located in the head of the engine cylinder and controlling both intake and exhaust operations. According to a preferred embodiment this 20 valve has a port which at the proper points of piston travel is carried into registry with intake and exhaust ports in the cylinder head. Preferably also the valve is held 25 yieldingly seated against this cylinder head and packing is provided to prevent leakage past the valve. Another feature of the invention is the mounting of the spark plug or other ignition device in a pocket in the 30 cylinder head and operating the same to fire the mixture through the port in the valve when said port registers therewith.

Other features and details of structure will appear as the specification proceeds.

35 The drawings illustrate the invention as embodied in several preferred forms but it will be understood that changes and modifications may be made within the scope of the appended claims without departing 40 from the true spirit and scope of the invention.

Figure 1, is a broken and more or less diagrammatic side elevation of an engine constructed in accordance with and embodying the invention.

Fig. 2, is a vertical sectional view of the same taken on a plane substantially at right angles to that of Fig. 1.

Fig. 3, is a broken plan view looking 50 down on top of the engine, the exhaust conduit having been removed to expose the top of the cylinder head and the intake manifold or conduit.

Figs. 4, 5 and 6 are plan views taken substantially on the plane of the line 4—6 of

Fig. 2, showing the valve in the "intake," "firing" and exhaust positions.

Fig. 7 is a plan view of the engine with the exhaust conduit in proper position. This view illustrates the placing of the 60 spark plug.

Fig. 8, is a vertical sectional view of a somewhat modified form of the valve construction.

Fig. 9, is a plan view of this construction.

Figs. 10 and 11 illustrate diagrammatically two modes of operating the valves in a multi-cylinder engine.

In the form of the invention illustrated 70 in the first seven figures, the engine cylinder 20 has two heads, 21 and 22, superposed one above the other with a space therebetween to receive the valve 23. This valve is shown in the form of a relatively 75 flat disk provided with a dependent flange or skirt 24 at the edge thereof fitting down over the top of the cylinder and having spur teeth 25 engaged by a driving pinion 26.

The cylinder heads are provided with a 80 series of aligned ports 30 forming intakes for the fuel and with another series of aligned ports 31 forming exhaust outlets. In the illustration there are four equidistantly spaced intake ports and four equidistantly 85 spaced exhaust ports, said ports being segmental in shape and the exhaust ports being somewhat larger than the intakes to allow for quick clearance of the burned charge. The valve is in this case provided with four equidistantly spaced segmental ports 32 and is rotated at a speed ratio of one to eight. That is, for each eight revolutions of the crank shaft 33, the valve will be rotated once. The gearing for accomplishing this may be of any suitable character, that shown, consisting of a bevel gear 34 on the crank shaft meshing with a bevel gear 35 on the upright shaft 36 which carries the valve-engaging pinion 26 on its upper end. The piston 37 and connecting rod 38 may be of any usual or preferred construction.

The valve is preferably maintained in self-seating engagement with the upper cylinder head, means for this purpose being shown in the form of spring-pressed rods 40 supporting a ball race 41 on which the flange 24 of the valve rides. This prevents 105 leakage between the valve and the upper 110

cylinder head and causes the valve to take up its own wear. The valve may be further guided by having a central stud 42, journaled between the cylinder heads.

- 5 Suitable packing is preferably provided to prevent leakage between the valve and the lower cylinder head, that shown in Fig. 2 comprising packing rings 45 seated in grooves in the outer wall of the cylinder and 10 engaging the inner surface of the flange of the valve. This provides a close joint and does not interfere with the proper seating of the valve.

The explosive mixture is admitted 15 through a conduit 50 having branches 51 covering the several intake ports and the exhaust is discharged through a conduit 52 which may be as indicated, in the form of a bell or dome covering the exhaust ports and 20 the branches of the intake as well. By this arrangement the exhaust gases serve to heat the intake manifold and thus warm the mixture entering the cylinder. The intake manifold may be made integral with the upper 25 cylinder head as indicated and be suitably bolted to the body of the cylinder, the line of separation between the cylinder and this head unit being indicated at 53. The exhaust conduit may simply be in the nature 30 of a cap slipped on over the neck of the intake as indicated at 54 and bolted down on top of the cylinder head by bolts 55, which bolts may be the same ones that secure the head in place.

- 35 A suitable ignition device is provided, the same being here shown as a spark plug 60 seated in a pocket 61 provided in the upper cylinder head and arranged to fire through an opening 62 in the lower cylinder head 40 when the port in the valve registers therewith. Suitable circuit connections by which this may be accomplished are indicated in Fig. 2 where 63 indicates a source of current, 64 a commutator on the crank shaft, 65 a 45 coil box and 66 a connection from the coil to the spark plug. The exhaust conduit is preferably recessed as indicated at 67 to receive the spark plug. This obviates the need for passing the plug down through the conduits and allows of the use of an ordinary sized plug.

In Fig. 2 the parts are illustrated as they appear on the firing stroke, the ports in the cylinder heads being closed by the solid portions of the valve. Fig. 4 shows the valve at commencement of the intake stroke, the ports 32 therein just commencing to register with the intake ports 30 in the heads and the piston being on its downward stroke. These 55 ports remain open during substantially the full downward stroke of the piston but are closed by the solid portions of the valve during the upward "compression" stroke of the piston. At or near the end of the compression stroke one of the ports 32 in the valve

registers with the ignition pocket 61 (Fig. 5) and the ignition device being thereupon operated, fires the charge down through such registered port and through the firing opening 62 in the lower cylinder head. At or 70 near the end of the downward firing or "power" stroke the ports 32 in the valve begin to register with the exhaust ports 31, (Fig. 6). These ports remain open during the upward "exhaust" stroke of the piston 75 but are closed before the next suction stroke commences (Fig. 4).

The admission and exhaust of the charges through a plurality of ports causes a full, quick intake of the fresh gases and a complete quick exhaust of the burned gases and also has the effect of keeping the parts properly cooled to a good working temperature. The registry of the valve ports with the ignition device is of sufficient duration to allow for the usual advance or retardation of ignition.

In the construction illustrated in Figs. 8 and 9 the valve 70 is located between upper and lower cylinder heads 71 and 72 but in this case only the upper head is ported. This upper cylinder head is shown as conical or tapering in form and the valve is similarly shaped so as to automatically seat itself as it wears down. The valve is held to its seat by a spring 73 coiled about the stem 74 of the valve and engaged between the drive gear 75 and a collar 76 on the end of the spindle. In this particular case also the cylinder head has only a single intake port 77 and a single exhaust port 78 and the valve has only a single port 79. This port in the valve extends inwardly from the bearing surface of the valve substantially at a right angle to such surface and thence straight on down through the neck portion 80 of the valve. The neck portion 80 is rotatably seated in the lower cylinder head 72 and packing rings 82 may be provided thereat to prevent leakage between the valve and this lower head.

The spark plug 85 is seated in a pocket 86 provided in the upper cylinder head and is operated to fire the charge down through the valve port 79 when said port registers therewith. In this construction it will be noted that the valve is relieved of all pressure of the explosion, as such pressure is taken up by the upper cylinder head through the valve port 79. The valve in the particular construction shown rotates once to each two revolutions of the crank shaft but if more ports were provided the valve would be rotated at a slower rate as will be understood from the description of the first construction shown.

In the case of a multi-cylinder engine suitable gearing will be provided for operating the valves in proper time. Fig. 10 illustrates how the valve gears 90 of all the cyl-

inders may mesh with one another and be driven by a single drive pinion 91. In Fig. 11 the valves are shown provided with worm gears 92 engaged by worms 93 on a common drive shaft 94.

The engine constructed in accordance with our invention is very simple, free from the complication of cams, rockers, etc., and is very quiet in operation. The terms which we have employed in disclosing the invention will be understood as used in a descriptive rather than in a limiting sense, except as may be required by the prior art. The term "rotary" as an instance, as applied to the valve is intended to comprehend a partial rotary as well as a full rotary movement of the valve.

What we claim is:—

1. In an internal combustion engine, a cylinder provided with superposed heads spaced one above the other and provided with segmental ports therein, said upper head having a pocket therein and said lower head having an opening in line with said pocket, an ignition device seated in said pocket, a valve rotatably engaged between said heads provided with a segmental port to register with the ports in the heads, means for rotating said valve and intake and exhaust conduits communicating with the ports in the upper cylinder head.

2. In an internal combustion engine, a cylinder provided with superposed heads spaced one above the other and provided with segmental ports therein, said upper head having a pocket and said lower head having an ignition opening in line with said pocket, an ignition device seated in said pocket, a valve rotatably engaged between the cylinder heads provided with segmental ports to register with the ports in the heads, means for operating the ignition device when the segmental ports in the valve register with the ignition opening in the lower cylinder head and intake and exhaust conduits communicating with the ports in the upper cylinder head.

3. In an internal combustion engine, a cylinder provided with superposed spaced heads having four equidistantly spaced segmental intake ports and four equidistantly spaced segmental exhaust ports therein, a valve rotatably engaged between said heads provided with four equidistantly spaced segmental slots therein, an intake conduit communicating with the four intake ports, an exhaust conduit communicating with the four exhaust ports, a crank shaft, a piston in the cylinder connected with said crank shaft, means operated by said crank shaft for rotating the valve once to each eight revolutions of the crank shaft and an ignition device operable at every quarter-revolution of the valve.

4. In an internal combustion engine, a cylinder provided with superposed spaced heads having a plurality of equidistantly spaced intake ports and the same number of equidistantly spaced exhaust ports therein, a valve rotatably engaged between said heads provided with equidistantly spaced ports equal in number to the number of intake ports in the cylinder head, an intake conduit communicating with the intake ports, an exhaust conduit communicating with the exhaust ports, a crank shaft, a piston in the cylinder connected with the crank shaft, means for rotating the valve once to a number of revolutions of the crank shaft corresponding to twice the number of ports in the valve and an ignition device operable at every second revolution of the crank shaft.

5. In an internal combustion engine, a cylinder provided with superposed spaced heads having segmental ports therein, a valve rotatably engaged between said heads provided with segmental ports to register with the ports in the heads, a ball race for supporting the valve, spring supports for said ball race and means for rotating the valve.

6. In an internal combustion engine, a cylinder provided with superposed spaced heads having segmental ports therein, a valve rotatably engaged between said heads provided with segmental ports to register with the ports in the heads, and with a dependent rim portion engaging over the outside of the cylinder, packing between said dependent rim portion and the outside of the cylinder and means for rotating the valve.

7. In an internal combustion engine, a cylinder provided with superposed heads spaced one above the other and having a plurality of registering intake ports and exhaust ports therein, an intake manifold having branches communicating with the several intake ports in the upper cylinder head, an exhaust conduit covering the exhaust ports in the upper cylinder head, a valve rotatably engaged between the heads provided with ports to register with the intake and exhaust ports and means for rotating said valve.

8. In an internal combustion engine, a cylinder provided with superposed heads having a plurality of registering equidistantly spaced intake ports and a plurality of equidistantly spaced exhaust ports therein, a valve rotatably engaged between said heads provided with a plurality of equidistantly spaced ports therein corresponding in number and spacing to the number of intake ports in the head, means for rotating said valve, an intake conduit communicating with the several intake ports in the head and an exhaust conduit communicating with the several exhaust ports in the head.

9. In an internal combustion engine, a cylinder provided with superposed heads having intake and exhaust ports therein, a valve rotatably engaged between said heads provided with a port therein for registry with the intake and exhaust ports, a ball race forming a bearing for the valve and spring pressed rods supporting said ball race to thereby yieldingly hold the valve seated against the upper cylinder head.

10. In an internal combustion engine, a cylinder provided with a head having a plurality of equidistantly spaced intake ports therein and a similar number of equidistantly spaced exhaust ports therein, a rotatable valve covering said cylinder head and provided with a plurality of equidistantly spaced ports therein corresponding

in number and spacing to the intake and exhaust ports respectively in the cylinder head, means for rotating said valve, an intake conduit having branches communicating with the several intake ports in the head, an exhaust conduit inclosing the branches of the intake conduit and communicating with the several exhaust ports in the head, an ignition device, said head and said valve having openings through which said ignition device fires the charge in the cylinder.
